UNITED STATES PATENT OFFICE.

ULYSSES G. LEE, OF CHATTANOOGA, TENNESSEE, ASSIGNOR TO MONTAGUE MAILING MACHINERY CO., A CORPORATION OF TENNESSEE.

ADDRESSING-MACHINE.

1,137,066.

Specification of Letters Patent. Patented Apr. 27, 1915.

Application filed July 11, 1912. Serial No. 708,921. Renewed June 5, 1913. Serial No. 772,000.

To all whom it may concern:

Be it known that I, ULYSSES G. LEE, citizen of the United States, residing at Chattanooga, Tennessee, have invented certain new and useful Improvements in Addressing-Machines, of which the following is a specification.

It is the object of my invention to provide a simple form of hand operated addressing apparatus adapted for office use, and in which a plurality of functions of the machine will follow as a result of operating the impression head.

The invention consists in the features of construction and combination and arrangement of parts hereinafter described and particularly defined by the appended claims.

In the accompanying drawings Figure 1 is a side view of an apparatus embodying my invention; and Fig. 2 is a plan view.

The apparatus is designed to work with individual address plates which are fed from the supply hopper to the impression point. The hopper is shown at 1 supported on a table 2. In this table are guided feed bars 3, which bars carry feed pawls 4 pivoted thereto at 5 and adapted to swing on said pivots, though being limited as to their movement by pins 6 entering openings 7 in the feed pawls or dogs. These pawls are spaced apart along the feed bars so that as they are reciprocated they will feed the plates from the hopper 1 step by step to the impression point to receive the impression from the pad or impression head 8 carried adjustably in an impression arm 9, which is composed of the side bars, as shown in Fig. 2, said side bars being connected by a cross member 10 and being mounted in the frame 40 by a shaft 11. This impression arm has a handle 12 by which the arm may be pressed down against the tension of a spring 13, which spring, when pressure is relieved from the handle, will cause the impression arm to swing upwardly. The feed slides are operated by arms 14 connected with the shaft 11, the lower ends of these arms being connected by a pin and slot with ears 15 depending from the feed slides. When the impression arm is forced downwardly, the feed slides will be moved rearwardly by means of the arms 14, and the feed dog at the right of the series will get behind the lowermost address plate in the hopper 1, and when the impression arm rises, the feed slides will be moved forwardly and the lowermost plate in the hopper will be moved from under the stack to a position to the left of said hopper. When the impression arm is again operated, a like action will take place to that just described, and the address plate which was previously moved from the hopper will be advanced another step toward the impression point until, by successive operations of the impression arm, this plate will arrive at the impression point to make the impression on the article to be addressed when the impression arm is again brought down. Aiding in this feeding action are pawls or dogs 4* carried pivotally by fixed bars 3* or other means of support, these dogs having no traversing action, but being pivoted each at one point adjacent the position of the movable feed dogs illustrated in Fig. 1, so that as the feed slides retract the fixed dogs will act as detents to hold the address plates in the position to which they have been advanced. It will be noticed that the hopper is located at the rear of the impression arm and the feed slides move in the same general direction in which the movement of the impression arm takes place, thus moving the address plates from in rear of the impression arm to a point along said arm where the impression is made by the impression head. After an address plate has been used, it is discharged from the table into a stacker chute 16, which has a follower 17 therein pressed upwardly by a spring 18. When several plates have collected on the follower 17, the weight of succeeding plates introduced into the stacker chute or hopper will cause the follower to move downwardly one step for each plate fed thereon. I also provide means for operating a ribbon from the movement of the impression arm. For this purpose a link 19 is connected with the arm 14, said link being slotted at 20 and receiving a pin on an arm 21 carrying a pawl 22 engaging a ratchet wheel 23 on a shaft 24. This shaft carries bevel pinions 25, 26, to mesh with pinions 27, 28, on shafts 29, suitably mounted and carrying the spools 30 for the inking ribbon. The shaft 24 is adjustable longitudinally so that either one of the pinions 25 or 26 may be engaged with its companion pinion while the connection is broken between the other pair of pinions, so that by adjusting this shaft the ribbon may be wound on either spool and unwound from

the other. The shaft, when adjusted, may be held by a latch 31 engaging circumferential grooves at 32 in the shaft, a set nut 33 being employed to fix the latch in position.

5 I claim as my invention:—

1. In addressing machines, the combination of a pivotally mounted hand operated impression arm, a hopper for address plates adjacent the pivot of the arm, a feed slide 10 moving under the hopper and in a direction transverse to the pivotal axis of the said pivot of the arm, a connection between the impression arm and the feed slide for operating said slide, an inking ribbon extending 15 transversely of the line of movement of the feed slide and of the impression arm, ribbon spools, and a connection from the impression arm for operating the ribbon spools, substantially as described.
2. In combination a hopper, a pivoted hand operated impression arm, a feed slide working under the hopper, ribbon spools to direct a ribbon transversely of the feed slide, an arm extending down from the pivoted 25 end of the impression arm connected with the feed slide, and a connection from said arm to the ribbon spools for operating the same, substantially as described.
3. In a manually operated addressing machine for printing from individual address plates, a frame, a straight runway for address plates, a hopper from which said straight runway leads, an impression arm pivotally mounted, a handle at the free end 35 of said arm, an inking ribbon extending over the impression point, an inking ribbon mechanism below the upper surface of the frame, an address plate feeder operating along the straight runway, and connections 40 from the impression arm to the address plate feeder and the inking ribbon mechanism, substantially as described.
4. In a manually operated addressing machine for printing from individual address plates, a frame, a hopper for address plates, an address plate feeder operating along a 45 straight path from the hopper to the im-

pression point, an inking ribbon mechanism including an inking ribbon extending over the impression point, a pivotally mounted impression arm having a handle at one end and an arm extending below its pivot at the other end, a connection between said arm and the address plate feeder and means for operating the inking ribbon mechanism 55 from the impression arm, substantially as described.

5. In combination, a table, an impression arm pivotally mounted and working above the table and having a handle at its free end 60 and operable by hand, a hopper for address plates, a reciprocatory feed slide for moving the plates from the hopper to the printing point, an inking ribbon extending over the impression point, inking ribbon 65 spools, and connections from the hand operated impression arm for giving the feed slide its reciprocatory movement and for giving the ribbon spools a step by step movement in one direction, substantially as 70 described.

6. In combination in an addressing machine, an address plate feeder, an impression arm arranged over the feeder and having a handle at its free end, said impression arm 75 having sides, a shaft extending across the path of the address plates, supports for the shaft outside the path of the plates, the said sides of the impression arm being mounted on said shaft, an impression pad extending 80 between the sides near their free ends, a hopper in rear of the impression arm and over the feeder, and means for operating the address plate feeder from the impression arm to move the address plates to the 85 impression point from the hopper, substantially as described.

In testimony whereof I affix my signature in presence of two witnesses.

ULYSSES G. LEE.
